Patented Apr. 6, 1915.

UNITED STATES PATENT OFFICE.

FREDERICK W. REINDEL, OF EAST CLEVELAND, OHIO.

EMBOSSING APPARATUS.

1,134,227.

Specification of Letters Patent.

Patented Apr. 6, 1915.

Application filed June 2, 1914. Serial No. 842,370.

Be it known that I, FREDERICK W. REINDEL, a citizen of the United States, and a resident of East Cleveland, county of Cuyahoga, and State of Ohio, have invented a new and useful Improvement in Embossing Apparatus, of which the following is a specification, the principle of the invention being herein explained and the best mode in which I have contemplated applying that principle, so as to distinguish it from other inventions.

The present improvements relate in general to book binding apparatus, and more particularly to a device for rapidly and conveniently applying the embossed lines, which are sometimes placed upon the covers of books for ornamental purposes, one such line often running vertically from top to bottom of the book at about the point where the back is joined to the cover.

My improved device is constructed to permit of continuous operation, and means are provided which maintain the embossing material in a semi-plastic condition thus causing the same to be readily and properly applied to the work in hand without sticking to the embossing wheel or roller. The device is also adjustable, adapting it to receive embossing wheels of various widths to operate on different work.

To the accomplishment of the foregoing and related ends, said invention, then, consists of the means hereinafter fully described and particularly pointed out in the claims.

The annexed drawing and the following description set forth in detail certain mechanism embodying the invention, such disclosed means constituting, however, but one of various mechanical forms in which the principle of the invention may be used.

In said annexed drawings:—Figure 1 is a view in perspective of my invention showing the same in position to operate upon a book; Fig. 2 is a plan view of the same showing the cover plate removed; Fig. 3 is a section on the line 3—3 in Fig. 2; Fig. 4 is a section on the line 4—4, Fig. 2; Fig. 5 is a section on the line 5—5, Fig. 2; and

Figs. 6 and 7 are diagrammatic views showing modifications.

Referring now to Fig. 1, the device will be seen to comprise a handle 1 which is preferably formed hollow and is provided at its outer end with a projecting shank or plate 2 having a circular offset disk 3, to which there is removably attached a shallow, preferably cylindrical, casing 4 open at one end. Such casing has an opening in its closed end which is closed by the disk 3 when the casing is mounted thereon. The disk 3 is provided with a threaded opening disposed concentrically with respect to said casing. Within the casing and attached to the closed end of the same is a concentric collar 6 extending to a level with the edge of the open end of the casing. Between the outer wall of the casing 4 and this collar 6 there is packed refractory material 7 in which is embedded a suitable electrical heating coil 8 having connection 44 extending through the hollow shank 2 and through the handle 1 where such connections or wires may terminate in a suitable block (not shown) adapted to be engaged in an electrical socket.

An embossing wheel or roller 9 is provided, which is centrally apertured, and is provided on its under side with a concentric collar 10 fitting loosely into the collar 6 formed in the casing. This collar 10 abuts against a thrust bearing consisting of a projection 11 formed integrally with the disk 3. When the collar 10 on the roller 9 is in operative contact with the projection 11 in the casing 4 the roller 9 is substantially in contact with the refractory material 7 in the casing, and is thus heated thereby when the electrical coil 8 is energized. The roller 9 is maintained in such position by means of a screw 12 provided with an enlarged portion 13 rotatably mounted in the aperture in the collar 10 on the roller and threaded beyond such point to removably engage in the threaded aperture 5 in the casing. This embossing roller is formed peripherally in the usual manner with a series of suitable designs adapted to transfer the embossing ma-

terial, such for example as gold leaf, to the work.

Mounted upon the shank 2 adjacent to the casing are two spaced plates 15 and 16, 5 upon the upper of which 16, is mounted a rotatable stud 17 adapted to receive a spool 18 upon which there is wound embossing ribbon 19, such ribbon consisting of a narrow strip of very thin paper upon the inner 10 side of which there is lightly attached thin gold leaf.

Mounted in the same plane as the embossing roller and upon the upper plate 16 is a feed roller 20. Such feed roller is rotatably 15 mounted upon a pin 21 attached to a slide 22 which is movably mounted in a slot 24 formed in the upper plate. A spring 23 is mounted between the two plates and bears against this slide and normally maintains 20 the same in such a position that the feed roller 20 is pressed closely against the embossing roller 9 thereby holding the embossing ribbon between the same and causing the feed roller to be operated upon rotation 25 of the embossing roller, this action causing the ribbon to be drawn between the two rollers, when the gold leaf will stick to the periphery of the embossing roller as will be readily understood. The feed roller is 30 preferably provided peripherally with a friction face 25 of some suitable material.

The paper strip of the ribbon 19 from which the leaf or other embossing material has been removed is passed around the feed 35 roller 20 between the latter and a smaller roller 26 which may be termed a discharge roller, which is mounted similarly to the feed roller upon a pin 27 projecting upwardly from a slide 28 mounted beneath the slot 40 formed in the upper plate between such plate and the lower one. A second spring 29 is provided for maintaining this discharge roller in operative position with respect to the feed roller. Operation of the embossing 45 roller 9 thus draws the ribbon 19 between the same and the feed roller 20 and causes the stripped ribbon to be discharged from between the feed and discharge rollers against a guideway 30 which causes the 50 same to pass out of the casing. A latch 45 or other means may be provided to hold the roller 20 out of engagement with the roller 9, such latch engaging behind the pin 21.

The embossing roller will be operated in 55 the direction of the arrow in Figs. 1 and 2, and will contact the work at the line indicated. Between such point of contact with the work where the leaf is removed from the surface of the embossing roller and 60 applied to the work and the point at which the embossing material is next applied to the roller, there are mounted means adapted to render the surface of the roller more adhesive to the embossing material than is the 65 ribbon thus causing the gold to be trans-

ferred from the ribbon to the embossing roller. A simple means for thus conditioning the roller comprises a lubricating cup 31 which is pivotally attached to the plate 15 and bears suitable fibrous material 32 70 soaked with oil and pressed normally against the surface of the embossing roller by means of a spring 33. This oil cup will spread a thin film of oil over the surface of the roller, and while the embossing material on the ribbon will stick to the periphery of the roller, it will not adhere thereto when the roller contacts the work by reason of the oily surface of the roller. The spring 33 is 75 adapted to maintain the cup 31 in either 80 operative or inoperative position as may be desired, such spring bearing against either of two flat sides on the cup as best shown in Fig. 2.

A third plate 34 is provided for the purpose of covering the various rollers mounted upon the second plate 16, such plate 34 being provided with open slots 35 removably engaging in coöperative slots 36 formed in the sides of two pins 37 mounted at the two 90 extremities of the plate. When the plate has been engaged with these two pins a slot 38 formed in the plate registers with the two pins 21 and 27 upon which are mounted the feed and discharge rollers, thus maintaining the latter in position but permitting the same to move as has already been described. A central aperture is formed in this cover plate adapted to receive a central screw 41 mounted on the second plate 16 100 and about such screw there is mounted a coiled spring 42 adapted to maintain the plate 34 away from the second plate. A knurled nut 43 is provided for adjusting the cover plate longitudinally of this screw 105 against the tension of the spring.

It will be understood that embossing rollers of various thicknesses may be used upon the same casing, it being only necessary to remove the screw 12 which engages the end 110 of the casing when the embossing roller may be lifted out and a different one inserted. In order to properly apply the embossing material to the surface of such new roller it is desirable to remove the feed roller and the spool and substitute a feed roller of a different thickness to correspond to the increased thickness of the embossing roller 115 and similarly a spool of wider ribbon will be mounted upon the rotatable stud. Although not absolutely essential in such circumstances, it is desirable to also provide a discharge roller of corresponding thickness, and this may be done if desired. The cover plate is then positioned with its slots engaging the coöperative slots formed in the upper ends of the two pins when the plate may be tightened against the rollers by the knurled nut or latch as already described.

In some cases it may be desired to use 120

ribbon in which the embossing material is on the outside of the paper. Under such conditions the spool 18 may be positioned upon the pin 21 on the slide 22, and will thus directly contact the periphery of the embossing roller 9, the waste ribbon being then led around the spool between the latter and the discharge roller. The operation of the device under these conditions will be readily understood, and it will be seen that the principle of operation is the same as when the feed roller is used to draw the ribbon between such roller and the embossing roller.

The appearance of the device when the spool 18 is mounted directly against the embossing roller is shown in Fig. 6, while in Fig. 7 I illustrate a roller 51 having a notch 52 adapted to receive the end of the stripped ribbon, which is then wound upon the roller 51, which may be displaced in the slot 24 to compensate for the increasing diameter.

My improved embossing tool possesses numerous advantages over the device now in general use for this purpose, in which merely a roller is provided which is first supplied with embossing material by being given a complete revolution when pressed against a supply of the material. This prevents the tool from forming continuously a line of greater length than the circumference of said roller. The present tool can be used continuously, since it is always supplied with embossing material by its own operation in the manner already described.

Other important features which coöperate to secure the results obtained with this device are the lubricating means and the means for heating the embossing roller. By making it possible to conveniently and quickly remove the various rollers the tool is given a wide range of use since other sets of roller of varying widths may be substituted, adapting the device to perform a number of kinds of work.

Other modes of applying the principle of my invention may be employed instead of the one explained, change being made as regards the mechanism herein disclosed, provided the means stated by any of the following claims or the equivalent of such stated means be employed.

I therefore particularly point out and distinctly claim as my invention:—

1. In a device of the character described, the combination of an embossing roller, a spool bearing thereon a strip of embossing ribbon, a feed roller movably mounted in the plane of said embossing roller to move toward or away from the latter, resilient means adapted to normally maintain said feed roller against said embossing roller with a uniform pressure, whereby operation of the latter causes rotation of said feed roller, thereby drawing such ribbon between the

two rollers, a lubricating device in peripheral contact with said embossing roller and adapted to lubricate the same before rotation into contact with such ribbon against said feed roller, and means adapted to guide such ribbon away from said embossing roller after the embossing material has been stripped therefrom.

2. In a device of the character described, the combination of an embossing roller, a spool bearing thereon a strip of embossing ribbon, a feed roller movably mounted in the plane of said embossing roller to move toward or away from the latter, resilient means adapted to normally maintain said feed roller against said embossing roller, whereby operation of the latter causes rotation of said feed roller, thereby drawing such ribbon between the two rollers, a lubricating device in peripheral contact with said embossing roller and adapted to lubricate the same before rotation into contact with such ribbon against said feed roller, and means adapted to guide such ribbon away from said embossing roller after the embossing material has been stripped therefrom, said means including a guideway and a roller operable by said feed roller.

3. In a device of the character described, the combination of a casing open at one end and having a central threaded aperture in the closed end and a thrust bearing block projecting into said casing, a heating coil concentrically mounted in said casing, a centrally apertured embossing roller mounted upon the open end of said casing and having a concentric collar extending into said casing and abutting against said thrust block; and a bolt passing through such aperture in said roller and journaling the same, said bolt also removably engaging in such threaded aperture in said casing.

4. In a device of the character described, the combination of an embossing roller, a spool bearing thereon a strip of embossing ribbon, a slide mounted to move toward and away from said embossing roller, a pin mounted on said slide, a feed roller rotatably mounted on said pin in the same plane as said embossing roller, resilient means adapted to normally maintain said slide in such a position that said feed roller presses such ribbon against said embossing roller, and a latch adapted to engage said pin and maintain said slide in a position preventing such operation of said feed roller.

5. In a device of the character described, the combination of a cylindrical casing open at one end, an embossing roller rotatably attached to said casing and closing the open end thereof, and heating means disposed in said casing in substantially lateral contact with said roller.

6. In a device of the character described,

the combination of a hollow handle, a cylindrical casing attached thereto and open at one end, an annularly arranged heating coil embedded in refractory material, the latter 5 filling said casing flush with the open end thereof, connections for said heating coil disposed in said hollow handle, and an embossing roller rotatably attached to said casing

in position to contact such refractory material therein.
